ABSTRACT OF THE DISCLOSURE

A sanding block for supporting a continuous loop sanding belt, which sanding block has first and second blocks positioned in the belt with adjacent ends of the block having aligned slots with inwardly inclined bottom surfaces in which opposing cam members are positioned for being moved inwardly and expanding the blocks in an outward longitudinal direction against the sanding belt making a rigid composite structure.

BACKGROUND OF THE INVENTION

Sanding blocks that expand within a continuous loop sanding belt and provide a composite sanding tool have many useful applications, both by the handyman and in industry. There are several known sanding block constructions that generally comprise a pair of co-planar members that are expanded longitudinally against the inner surface of the continuous loop sanding belt. At least one type sanding block employs spring means to force the blocks apart and against the loop sanding belt. These spring biased blocks have the disadvantage of not providing a rigid internal structure for the sanding belt. Rather the two blocks are capable of being moved towards each other against the spring force during sanding, which loosens the belt. Other means are often used to expand the blocks, such as wedges being driven between the blocks and the use of a bolt that is aligned between the blocks and is forced outwardly to move one block in a direction away from the other block. These other known structures have the disadvantage of utilizing a means that when one placed in position is difficult to remove, as is necessary when a new sanding belt is placed on the sanding belt block. In others of the known means, there is no side uniformity of displacement of one block relative to the other block. This allows side sway with a greater tension being applied to one side of the continuous loop sanding belt than is applied to the other side.

It is thus advantageous to have a sanding block for supporting a continuous loop sanding belt that is rigid and strong in construction, is capable of expanding or forcing one block in a direction away from the other block in an efficient, uniform and positive manner in which the displacement on both sides of the respective blocks is held uniform and which block is quick and easy to operate, is inexpensive to construct, and is rigid and durable in construction.

SUMMARY OF THE INVENTION

The embodiments of the sanding block of this invention generally comprise first and second substantially rectangular blocks that, in the operative position, are in

2

longitudinal, co-planer alignment. The blocks are generally constructed of solid material with one of the blocks having a longitudinal length that is substantially greater than the other block. The facing or adjacent ends of each of the blocks have a longitudinal slot extending from one side of the ends to the other. The slots are formed with upper and lower lips that define a slot volume aligned through the mid-point of each block in a direction normal to the longitudinal axis of the blocks. The bottom surfaces of each of the slots in each of the blocks are inclined inwardly in a direction toward the end surfaces and at a slight angle to a plane normal to the longitudinal axis of the blocks. Thus the adjacent slots in the facing ends of the blocks have similar inclined surfaces.

10 Positioned in the slots at each adjoining end are identical cam members having a thickness corresponding to the spacing between the sides of the slots and having opposite inclined surfaces that mate with the aforesaid inclined slot surfaces. A bolt having oppositely wound spiral threads engage threads in the respective cam members. Upon turning the bolt, the cam members are drawn together and up the inclined surfaces of the slots, forcing the block members in opposite directions away from each other and thereby expanding against the inner surfaces 15 of the continuous loop sanding belt. This tightens the belt in such a manner that the curved end surface of one of the blocks provides a curved sanding surface and on the other end of the block a sanding surface with sharp square edges.

20 It is therefore an object of this invention to provide a new and improved sanding block.

25 It is another object of this invention to provide a new and improved sanding block for supporting a continuous loop sanding belt.

30 It is another object of this invention to provide a new and improved sanding block for supporting a continuous loop sanding belt that is rigid in construction and final assembly, is easy and inexpensive to manufacture, and is easily assembled and disassembled.

35 It is another object of this invention to provide a new and improved sanding block for supporting a continuous loop sanding belt that provides uniform and rigid movement of each side of the opposing block members, one relative to the other, to provide uniform expansive pressure across 40 the entire width of the sanding belt in the longitudinal direction.

45 These and other objects of my invention will become more apparent upon a reading of the following detailed specification and an examination of the drawings in which like reference numerals identify like parts throughout 50 the views of the drawings and in which:

55 FIG. 1 is a perspective view of an embodiment of this invention in the operative condition with the continuous loop sanding belt mounted thereon.

FIG. 2 is an exploded perspective view of the operative mechanism of one of the embodiments of my invention.

FIG. 3 is an exploded view of another operating mechanism for use in my invention.

Referring now to FIGS. 1 and 2, the embodiments of the sanding block comprises a first block 12 and a second block 10. The two blocks have a substantially rectangular shape with flat co-planar surfaces longitudinally arranged in the operative position. As may be seen, the second

block 10 is substantially longer than the first block 12 with each block having a solid construction. The blocks may be made of wood, plastic, or any other suitable material and have finger gripping recesses 52 on the sides thereof for facilitating use.

A continuous loop sanding belt 26 may have any suitable surface, such as would comprise a finishing sanding belt, a rough cut sanding belt, or abrasion belts. The continuous loop sanding belt encloses the first and second blocks in the longitudinal direction in the manner illustrated and upon lengthwise expansion or movement of the blocks 10 and 12, the blocks move out against the belt holding the entire device in a rigid combined structure. The front of block 12 has a curved surface 48 and the rear edge of the block 10 has sharp square edges. The belt 26 has a width that exactly conforms with the width of the blocks 10 and 12. It may thus be understood that the sanding block has particular advantageous uses in being able to sand curving surfaces with the curved end and to sand corners and edges with the sharp end edges 50. Further by utilizing a quick and easy operating mechanism for expanding the two blocks, the sanding belt 26 may be suitably rotated on the sanding block structure to provide new sanding edge surfaces at the respective ends of blocks 10 and 12.

The adjacent or opposing faces of blocks 10 and 12 have slots 14 and 16 that pass from one side of the block to the other in the centered portion thereof. Each of the slots have end projections 44 and 46 with a given lateral space therebetween and have bottom surfaces that are inclined inwardly from each side forming inclined surfaces 18, 19, 20 and 21. A pair of cam members 22 and 24 have thicknesses substantially corresponding to the distances between the projection members 44 and 46 and thus fit therebetween. The cam members each have inclined surfaces 30 and 32 that rest against the respective inclined surfaces in the slots 14 and 16. The cam members 22 and 24 are interconnected by bolt 28 that has oppositely spiraled threads 34 and 36 with a center circumferential groove 38 that is aligned with the mid-point of the respective blocks 10 and 12. The head of the bolt 28 projects out through one side of the cam members 22 thus providing means for turning the bolt in the normal manner. It may be seen that by turning the bolt 28, the cam members 22 and 24 are either pulled toward each other or are moved away from each other in equal amounts. A U-shaped wire slip 40 fits into groove 38 with the ends projecting into the openings 42 in the bottom of the slot 14 of block 10 and holds the bolt member 28 and cam blocks 22 and 24 in retained, aligned position during assembly.

In operation, the cam members 22 and 24 are inserted into the slot 14 and wire slip 40 is passed over groove 38 with the ends of the slip being inserted into openings 42. The first block 12 is then slidably positioned over the projecting sides of cams 22 and 24 and the continuous loop sanding belt 26 is placed around the longitudinal outer surfaces of the blocks. The bolt 28 is then rotated in the normal manner by a screwdriver or like tool drawing cam members 22 and 24 together and up the inclined surfaces 18, 19, 20 and 21 forcing outward movement of the first and second blocks in a direction away from each other and tensioning belt 26. In this assembly the blocks 10 and 12 are originally positioned in an aligned co-planar relationship and the cam members 22 and 24, being identical, create an equal force on each side of the block that holds the entire structure in a rigid and supported alignment. The block is disassembled by reverse application of the previously described procedure allowing the sanding belt to be either removed or changed in position on the sanding block.

Referring to FIG. 3, the structure of the sanding block in this embodiment is substantially the same as that described relative to FIGS. 1 and 2, with the difference being that slots 60 and 82 have different means for holding the

5 bolt 80 and cam members 72 and 74 in position. The second block 56, corresponding to block 10 in FIG. 2, has forward projecting portions 66 and 68 with a slot 70 therebetween. The first block 58 has a recessed vertical opening 86 for receiving the projections 66 and 68. Bolt 80 has a wide circumferential groove 78 that fits in the slot 70 with the edges of the groove 78 substantially abutting the sides 77 of the projections 66 and 68. Accordingly the projections 66 and 68 and slot 70 function to hold the bolt 80 and the cam members 72 and 74 in the desired oriented position relative to the slots 60 and 82 and the inclined surfaces 62 and 84. The operation of the block illustrated in FIG. 3 is the same as that previously described relative to FIG. 2. The cam members 72 and 74 and 20 22 and 24 may be made of metal, plastic, or any other suitable rigid material.

Other objects, advantages, and modifications of my invention will be apparent to those skilled in the art, all of which I desire to cover within the scope of the attached 25 claims.

Having thus described my invention, I now claim:

1. A sanding block for supporting a continuous loop sanding belt comprising, first and second blocks, said blocks in the operative position being in longitudinal co-planar alignment, the adjacent end surfaces of each of said blocks having aligned slots with inwardly inclined bottom surfaces extending from each side of said blocks, a pair of opposing cam members having inclined side surfaces for fitting in said slots and resting against said inclined bottom surfaces of said slots, and means interconnecting said cam members for moving said cam members toward each other and up said inclined surfaces of said slots forcing said blocks in a direction away from each other.
2. A sanding block for supporting a continuous loop sanding belt as claimed in claim 1 in which, said inclined bottom surfaces in each of said slots comprising a pair of surfaces that incline in a direction toward said end surfaces.
3. A sanding block for supporting a continuous loop sanding belt as claimed in claim 1 in which, said interconnecting means comprising a connecting bolt having oppositely spiraled threads on each end that threadably engage threads in said cam members.
4. A sanding block for supporting a continuous loop sanding belt as claimed in claim 3 in which, said bolt having a circumferential recessed portion adjacent the aligned centers of said slots, and holding means on at least one of said blocks for fitting into said recessed portion and holding said bolt in a centered position relative to said slots.
5. A sanding block for supporting a continuous loop sanding belt as claimed in claim 4 in which, said circumferential recessed portion comprising a groove, and said holding means comprising a U-shaped member for fitting in said groove with the ends of said U-shaped member projecting into holes in the end of one of said blocks.
6. A sanding block for supporting a continuous loop sanding belt as claimed in claim 4 in which, said circumferential recessed portion comprising a groove, and said holding means comprising a portion of said one of said blocks that extends longitudinally from said end surface and has a recess with side walls that fit over the recessed portion of said groove.
7. A sanding block for supporting a continuous loop sanding belt as claimed in claim 1 in which, the opposite end of said first block having a curved surface, and the opposite end of said second block having a square shape with sharp edges.

8. A sanding block for supporting a continuous loop sanding belt as claimed in claim 1 in which,
 both of said blocks having a solid construction,
 and said second block having a substantially greater length in the longitudinal direction than said first block.
9. A sanding block for supporting a continuous loop sanding belt as claimed in claim 1 in which,
 a continuous loop sanding belt,
 said first and second blocks being held in the operative position by said sanding belt,
 and said cam members in cooperation with said interconnecting means moving said blocks outwardly in

the longitudinal direction to expand against said sanding belt forming a rigid structure.
